AMUSEMENT APPARATUS

Nathan D. Wyckoff, Sterling, Ill.

Application June 18, 1941, Serial No. 398,514

11 Claims. (Cl. 312—55)

1

This invention relates to amusement apparatus and more particularly to amusement apparatus whereby games ordinarily requiring a play director may be played by one or more persons without the assistance of the normally required play director.

Many games which have a wide appeal are of such a nature as to require a play director who by vocal or visual means directs the play of the several players of the game, and in such games, in order to justify the trouble or expense incident to the provision of such a play director, it is necessary that the game be played by a relatively large number of people. An example of such a game is the game which is popularly known under the name of Bingo, although it is applicant's understanding that games of a similar character are played under a variety of different names in different parts of the country. In the game of Bingo it is customary for each of the players to be provided with a playing card, and after all of the players have received such cards, the play director calls off combinations of numbers and letters which may or may not be present in the various designated areas of the playing cards of the various players, and each player marks or otherwise designates the particular portion or area of his playing card upon which the called letter-number combinations are found upon his playing card. The objective of this particular game as normally conducted is to obtain upon a playing card a line of five numbers which have been called by the play director, and the first one of the players to attain this line of called numbers is designated the winner.

The primary object of the present invention is to enable games of this character, and particularly the game known as Bingo, to be played without the services of a play director.

A further object of this invention is to enable games of this character which normally require a relatively large number of players, to be played by one player, without the services of a play director, and yet to enable the game to be played with the same apparatus by a relatively large number of players.

A further object of this invention is to enable games of the aforesaid character to be played with an apparatus which is adapted to be governed by coin controlled means; and a further object ancillary to the foregoing is to enable such coin controlled apparatus to be constructed so as to be conveniently operated without the necessity for extensive instructions to the players. Further objects related to the foregoing are to

2

insure that the coin controlled game apparatus cannot be fraudulently operated; to prevent retention of coins when the supply of playing cards has been exhausted; to enable a relatively large number of different series of play directions to be used in such an amusement apparatus; and to provide a phonographic play-directing means in such a game apparatus which is interrelated with the automatic starting means in such a manner as to cause different play directions to be given in at least some of the succeeding operations of the game apparatus.

Other objects and advantages will become apparent from the following description and claims and from the accompanying drawings which illustrate a preferred embodiment of the invention.

In the drawings:

Fig. 1 is a front elevational view of an amusement apparatus embodying the features of the invention;

Fig. 2 is a side elevational view of the amusement apparatus shown in Fig. 1;

Fig. 3 is a rear elevational view of the upper portion of the apparatus, the rear panel or wall being removed to illustrate details of internal construction;

Fig. 3A is a rear elevational view of the lower portion of the amusement apparatus, the rear panel or wall being removed to illustrate the details of internal construction;

Fig. 4 is a plan section taken along the line 4—4 of Fig. 3A;

Fig. 5 is a fragmental elevational view as viewed from the line 5—5 of Fig. 4;

Fig. 5A is a fragmentary perspective view showing a part of the phonograph control mechanism;

Fig. 6 is a vertical sectional view taken substantially along the line 6—6 in Fig. 3 and illustrating the details of construction of the playing card vending means;

Fig. 7 is a sectional view of the lower portion of the magazine of the playing card vending means;

Fig. 8 is a schematic wiring diagram illustrating the manner in which the various operative mechanisms are electrically connected; and

Fig. 9 is a front elevational view of one of the playing cards used with the amusement apparatus herein illustrated.

For purposes of disclosure a single form of the invention is illustrated in the drawings and will hereinafter be described in detail as incorporated in a particular form of cabinet and as applied to the playing of a particular game, but it is to be understood that this disclosure is not intended as

a limitation of the invention to this particular form of cabinet or to the playing of the particular game with reference to which the invention is herein described, it being contemplated that various changes might be made by those skilled in the art to adapt the invention to other forms of cabinets and to the playing of other games without departing from the spirit and scope of the invention as defined by the appended claims.

In the form chosen for disclosure herein the invention is embodied in a game apparatus of the coin controlled type, mounted in a sectional cabinet 10, and particularly adapted for playing the game popularly known as Bingo. The invention provides, within the cabinet 10, a means for vending playing cards with which the game may be played by one or more persons, and there is also provided within the cabinet a play-directing means which, in the form chosen for disclosure, is in the form of a phonographic reproducing means 13 having one or more phonograph records 14 which in their sound track or tracks carry recorded playing instructions or directions which are reproduced audibly through the medium of a loud speaker 15 and an associated amplifier 16.

The playing cards 17 for the game are arranged to be vended from one or more vending devices 18 mounted within the cabinet 10 and operable individually by means including manual operating plungers 20. The playing cards 17 are, of course, vended to the prospective players before the phonographic reproducing means 13 is set into operation, and in the present instance the vending of such playing cards 17 is coin controlled through the medium of one or more coin slot mechanisms 22, one of which is associated with each of the playing card vending devices 18, and in order to prevent operation of the phonographic play-directing means 13 during undesired intervals or prior to the time when the players are ready to mark their playing cards, the operation of such phonographic means 13 is rendered dependent upon the operation of the card vending devices 18 so as to be operable only after the vending of one or more playing cards by the vending devices. In the present instance the phonographic reproducing means is arranged for operation under a manually controlled starting means, this starting means being conditioned for operation as an incident to the operation of one of the playing card vending devices 18 through a vending cycle, and by reason of this arrangement, the operation of the phonographic reproducing means 13 is placed under the control of the player or players to the end that such players may operate the playing card vending means to obtain a relatively large number of playing cards 17 before the phonographic reproducing means 13 is rendered operative. Thus the play directions are rendered available by the operation of one of the playing card vending devices 18, but are delayed until such time as the players are ready to play the game. A player then manually actuates the starting means, and the play-directing means provided by the phonographic reproducing means 13 starts upon a play-directing cycle, and upon completion of the play-directing cycle, the operation of the phonographic reproducing means is automatically terminated. As an incident to the starting of the phonographic reproducing means 13 by the manual starting means, the manual starting means is automatically rendered ineffective to produce another starting op-

eration, so that the starting means remains ineffective until a playing card vending means 18 is again operated to vend one or more playing cards 17.

5 In the present instance the manual starting means which is to be operated by the player to initiate operation of the phonographic reproducing means 13 is in the nature of an electrical means which is energized through actuation of a control element provided by a normally open push button switch 25, this switch 25 forming part of an energizing circuit which is conditioned for closure as an incident to the operation of one or the other of the playing card vending devices 18.

15 As hereinbefore pointed out the present invention is adapted for use in playing a variety of different games, but as herein shown, the apparatus is particularly adapted for playing of the game known as "Bingo." A playing card 17

20 for use in playing the game of Bingo is illustrated in Fig. 9 of the drawings wherein it will be evident that the card is divided in the conventional manner into five vertical columns, and

25 the letters of the name Bingo are printed at the upper ends of the successive columns. Thus the first column is identified by the letter B, the second by the letter I, the third by the letter N, the fourth by the letter G, and the last or fifth

30 column by the letter O. The several columns, below the identifying letters, are divided into five transverse divisions so that a playing field is provided having 25 squares arranged 5 in a vertical direction and 5 in a horizontal direction.

35 Cards of this character are prepared as by printing so as to include different variantly arranged number in each of these squares, the squares in the B column being usually arranged to bear five numbers falling in the range between 1 and 15 inclusive, the I column being arranged to have various numbers printed in the squares thereof with the numbers in this column falling between 16 and 30 inclusive, the numbers employed in the

40 "N" column usually fall between 31 and 45 inclusive, those in the G column between 46 and 60 inclusive, while those in the O column usually fall between 61 and 75 inclusive. In most instances the central square of the middle column is designated as a "free" square. The numbers

45 and the arrangement of numbers carried by the individual playing cards 17 are varied considerably in an assortment of such cards, and when the play director or play-directing means calls off a limited series of numbers falling within the

50 range of 1 to 75 inclusive, the players mark those numbers which have been called and which they find upon their card. The objective of the game is to find a series of five called numbers which are disposed on a playing card in a straight line,

55 60 the central or "free" square being effective in certain instances as a number in providing such a winning straight line combination of numbers.

In the present amusement apparatus I have found it advantageous to so prepare the play-directing records 14 that a series of 25 numbers, falling within the range of 1 to 75 inclusive, are called during a cycle of operation of the apparatus, and in accordance with the usual practice, each such number is prefaced by calling of the letter which identifies the column in which the number is normally found. Actual calling of the identifying letter would not, of course, be essential, but is in accordance with the usual practice employed in playing this particular game.

70 75 In the amusement apparatus of the present in-

vention it would be possible to vend the playing cards 17 to the players from a single vending device 18, but I prefer to provide a plurality of such vending devices 18 in order that the players may obtain the desired playing cards more readily, and for the further reason that such a plurality of vending devices affords an element of selection which the players may desire to exercise. The playing card vending devices 18 are, in the present instance, mounted in an upper section 10A of the cabinet 10, one such vending device 18 being disposed adjacent to each of the side walls 27 of the cabinet section 10A as shown in Fig. 3 of the drawings. Each vending device 18 includes an upstanding supply magazine 28 in which a stack of playing cards 17 is adapted to be arranged each in a flat or horizontal position, the magazine having a removable rear wall 29 held in place by a latch device 30 to facilitate loading of the magazine. The playing cards 17 are arranged with a weight 31 on top of the stack thereof so as to insure proper downward feeding movement of the playing cards 17 within the magazine 28, and the lower playing card 17 rests on a feeding slide 32 which is mounted for reciprocation beneath the lower end of the magazine 28. The feeding slide 32 has a plate member 33 mounted thereon which normally underlies the lower playing cards 17, and a forwardly facing shoulder 34 is provided by the plate 33 so that when the feeding slide 32 is reciprocated rearwardly, or to the left as viewed in Fig. 6, the plate 33 is withdrawn rearwardly from beneath the lowermost playing cards 17 and the shoulder 34 is disposed rearwardly of the rear edge of the lowermost playing card. When the feeding slide 32 is thereafter withdrawn in a forward direction, or to the right in Fig. 6 of the drawings, the feeding slide advances the lowermost playing card along a guideway provided by stationary upper and lower plates 35 and 36. After the initial loading of the magazine the first two reciprocatory strokes of the feeding slide 32 are in a sense idle strokes since the guideway is relatively long and it is only during the third feeding stroke that the leading playing card 17 is discharged from the forward face of the cabinet section 10A through a vending slot 37 which is provided in the forward wall 38 of the cabinet section 10A.

The feeding plunger 20 of each card vending device is utilized for imparting such forward feeding movement to the feed slide 32, this plunger extending rearwardly through the forward wall 38 and having a head 40 at its rear end adapted, in forward or outward withdrawing movement of the plunger, to engage a downwardly projecting flange 41 provided on the feed slide 32. The plunger 20 is normally urged rearwardly to the position shown in Fig. 6 by an expansive coil spring 42, and when so positioned the head of the plunger is engaged with a buffer spring 43 which surrounds the plunger between the head and a bearing element 44 which supports the plunger 20.

The feeding slide 32 normally assumes the position shown in Fig. 6 so that withdrawal of the plunger 20 is ineffective to feed or vend a playing card 17; and in order to condition the vending device for a vending operation it is essential to withdraw the feeding slide 32 to the rear, or to the left in Fig. 6 until a card 17 is dropped in front of the shoulder 34. The plunger 20 may then be withdrawn to discharge the leading card 17 from the vending slot 37. The desired conditioning of the vending device 18 is attained under

the control of the coin actuated mechanism 22, and in the present instance the slide 32 is retracted by electrical means in the form of a solenoid 46 having its armature 47 connected to the flange 41. Thus when the solenoid 46 is momentarily energized, the armature 47 thereof draws the slide 32 rearwardly and conditions the device for the vending of a playing card 17.

The energization of the solenoid 46 takes place under the control of the coin operated mechanism 22, and this mechanism may be of any conventional type. In the form illustrated two such coin slot mechanisms 22 are provided, one controlling each of the two card vending devices 18. Each coin slot mechanism 22 as herein shown comprises an entry slot 49 in the forward face of the cabinet section 10A, and a coin inserted into the slot 49 travels downwardly along a guideway 50 into a housing 51 within which conventional means tests the coin to detect at least certain types of fraudulent devices or slugs. If the coin is a proper one it is discharged downwardly from the housing 51 into a guide chute 53 down which it rolls into a coin box 54 housed within the cabinet section 10A. As the coin is discharged at 52 from the coin slot housing 51, it actuates one end of a lever 56, and the other end of this lever 56 is thus caused momentarily to close both switches 58 and 59 of a switch means 60. Closure of the switch 58, through circuit connections to be hereinafter described in detail, serves to energize the solenoid 46 of the associated card vending device 18, thereby to condition the same for a vending operation.

Coin slot mechanism such as that indicated at 35 22 are customarily provided with a coin rejecting or returning means, and such conventional means are in many instances rendered operative by manual actuation of means such as a spring biased return button 63 which, as shown in Fig. 6, actuates a bell crank 64. The bell crank 64 is operative in a conventional and well known manner, when actuated by the button 63, to cause a coin which is passing through the mechanism to be discharged into a return pocket 68 rather than into the chute 53; and the user may retrieve the coin from the return pocket 68.

In accordance with the present invention this coin rejecting or returning mechanism is utilized to automatically prevent retention of coins 50 when the associated card-supply magazine is empty or nearly empty. To this end a solenoid 70 is mounted rearwardly of and in alignment with the button 63, and its armature 71 is connected as by a wire 72 to one arm of the bell 55 crank 64. The arrangement is such that when the solenoid 70 is energized the coin rejecting mechanism is rendered operative. As shown in Fig. 6, the resulting coin rejecting action is maintained through the medium of a latch 73 which 60 engages a notch 74 in the armature 71 to retain it in the rearward or active position to which it is actuated when the solenoid is energized.

To cause the solenoid 70 to be energized a detecting means is associated with the supply magazine 28, as shown in Fig. 7. Thus a bracket 75 supports a horizontally slideable plunger 76 beside the magazine 28 so that one end of the plunger 76 extends through the adjacent wall of the magazine and bears against the edges of the card 17. The plunger 76 is urged against the cards 17 by a spring 77, and is so positioned vertically that when the last card 17 is being fed from the magazine, the plunger 76 shifts into the magazine, over the top of the weight 31. Such inward movement constitutes the de-

tecting movement of the plunger 76, and is arranged to cause momentary closure of a switch 79 carried on the bracket 75. To this end a lever 80 has one end bearing against one spring blade or contact of the switch 79, and the other arm located in the path of a head 81 formed on the plunger 76. The arrangement is such that in a detecting movement of the plunger 76 the head 81 rocks the lever 80 to cause momentary closure of the switch 79, and then passes freely beyond the lower end of the lever 80 so as to permit reopening of the switch 79. The switch 79 is connected, as will hereinafter be described, to the related solenoid 78 so as to cause the solenoid to be momentarily energized when the feeding of the last card 17 from the magazine. Thus the coin return means is actuated to and latched in its active position when the supply of cards in an associated card vending device runs low, and the coin return means is maintained active and all coins are returned until such time as the magazine is refilled.

After the vending of the playing cards 17 has been completed, and the player or players start the play-directing means by actuation of the starting button or switch 25, the automatic phonographic reproducing means 13 is started upon an operative cycle wherein a complete set of play directions is reproduced from one of the phonographic records 14. As hereinbefore pointed out, the phonographic reproducing means 13 is herein shown as being of the type wherein a different record is played during succeeding cycles of operation, but it will be understood that in many instances it may be possible to utilize but a single record 14. The phonographic reproducing means may be of many different types so long as it embodies means for automatically terminating its operation after a complete set of play directions has been reproduced. The mechanism shown herein is best illustrated in Figs. 3A and 4, and this mechanism constitutes a modification of a commercial phonograph unit produced by J. P. Seeburg Corporation, of Chicago, Illinois, this unit having been modified so as to reduce the number of turntables 85 upon which records 14 are supported to eliminate manual selectivity with respect to the records, and such modification reduces to some extent the automatic variation or selection of the records 14 in successive cycles of operation. Since the phonographic reproducing means is in a basic sense a commercial unit, it will be described herein only in so far as is necessary for a complete understanding of the operation of the present amusement apparatus.

Thus as shown in Figs. 3A and 4 the phonographic reproducing means comprises a mounting plate 86 beneath which a frame structure 87 is carried, the mounting plate 86 being supported on brackets 87' within the lower cabinet section 88 on a yielding mounting 83. On the frame structure 87 a driving motor 89 is mounted and this motor through the medium of a suitable reduction gearing 90 is operable to drive a vertically extending shaft 91 upon which the several turntables 85 are mounted just above the mounting plate 86. A removable bearing 93 engages the upper end of the shaft 91 to impart stability thereto.

The phonographic reproducing means provides a tone arm 95 mounted on a carriage mechanism 98 which is vertically slidable along a supporting shaft 97 so that the tone arm may be moved to a proper level for operative engage-

ment with any one of the records 14. Generally considered, the tone arm is first moved to the desired vertical level by a yielding means, the extent of movement being determined by stop devices 98 or 99 selectively which are engaged by a stop arm 100 mounted on the carriage 96, and after the tone arm has reached the selected level, it is moved laterally to a position over the record, this lateral shifting being attained by a 10 rotative movement imparted to the carriage 96 about the axis of the shaft 97. The tone arm is then lowered to engage the sound track of the selected record 14, and thereafter the tone arm follows the sound track until it reaches the stopping groove adjacent to the central portion of the record, at which time a stopping mechanism is actuated to return the tone arm to its normal position and cause the phonographic mechanism to terminate its cycle of operation.

The operation as outlined generally in the preceding paragraph is attained primarily by cam means, such cam means being mounted upon a cam shaft 101 which is mounted in the supporting frame 87 rearwardly of the shaft 91 and in a horizontal location. A worm 102 on the shaft 91 drives a worm wheel 103 which is loosely mounted on the shaft 101, and a normally engaged clutch device 104 is provided for causing the worm wheel 103 to drive the cam shaft 101. The clutch 104 has its driven element urged in a right-hand or clutch-engaging direction by a spring 104', Fig. 4, so as to tend normally to engage and cause the shaft 101 to be driven by the gear 103, and the engagement and disengagement of the clutch is controlled by a throw-out lever 105 which engages a cam surface 106 on the driven clutch element to disengage the clutch after the driven member of the clutch, and the cam shaft 101, have been rotated through substantially one-half revolution to what may be termed an intermediate stop position. It is during this first one-half revolution of the cam shaft 101 that the tone arm is manipulated to start the operation of the reproducing means, and after such operation has started the throw-out lever 105 disengages the clutch 104 so that the cam shaft 101 remains stationary. The throw-out lever 105 is pivoted intermediate its ends on a stationary horizontal shaft 105', and a torsion spring 103' acting between the shaft 105' and the lever 105 urges the rear end of the lever toward its action position against the side or periphery of the driven element of the clutch 104. When the tone arm reaches the stopping groove 55 of a record, the carriage 96 is rapidly rotated in a clockwise direction as viewed in Fig. 4, and means on the end of an arm 108 engages a cam surface 109 formed on the forward end of the throw-out lever 105, and this rocks the lever 105 about the shaft 105' so as to raise the rear end of the lever 105 and thereby disengage the same from the cam surface 106. The driven member of the clutch 104 is thereby released from the clutch-disengaging action of the lever 105, and the spring 104' moves the clutch-element to its clutch-engaged position wherein the clutch is effective to drive the cam shaft 101. Thus the cam shaft 101 is driven through the second one-half of its cycle, during which movement the tone arm is moved in a counterclockwise direction, Fig. 4, so as to be disposed outside of or beyond the edges of the record tables, and the tone arm is then restored to its inactive lowered relationship, and a stop arm 110 on the cam shaft 101 operates upon a switch arm 111' of a switch

111 to break the circuit to the motor 89 and thereby stop operation of the phonographic reproducing means. The means for accomplishing these operations are described hereinafter.

The vertical movement of the tone arm carriage 96 is governed by a cam 115 on the cam shaft 101, which acts through a lever 116 and a link 117 to shift the carriage 96 downwardly against the force of a spring means 118. Thus during the last half of the cycle, the carriage 96 is forced downwardly, while during the first half of the cycle it is permitted by the cam 115 to move upwardly until the stop finger 100 strikes a stop 98 or 99. The stop 99 constitutes a disk notched so as to form a plurality of circumferentially spaced radial fingers, which may or may not be in the path of the stop finger 100, and hence the carriage may travel upwardly in some instances until the disk-like stop 98 is effective. The stops 98 and 99 are mounted on a vertical shaft 119 which in each cycle of operation of the device is rotated for a short distance by gearing 120 and cam means 120' associated with the cam shaft 101, so as to render the stops 98 and 99 variably effective. The means for thus operating the gearing 120 may be of any conventional type such as the ratchet means shown in Fig. 5A. In this construction a bell crank 120A has one arm thereof operatively connected to the cam means 120', while the other arm of the bell crank 120A is connected by a link 120C to a ratchet arm 120D. The pawl of the ratchet arm 120D acts on a ratchet 120E connected to the gear 120F of the gearing 120 to advance the gear 120F through an indexing movement each time the cam shaft 101 is rotated through the last half of its cycle. In the event that the lower turntable 85 is to be used, another angularly and downwardly displaced stop element such as the stop 99 would, of course, be provided on the shaft 119.

Appropriate and timed lateral shifting of the tone arm 95 is attained by a cam 121 on the shaft 101, which acts through a medially pivoted arm 122 and a roller 123 on the arm 122 to engage a curved cam surface 124 provided on the carriage 96. The arm 122 is pivoted on the shaft 105'. The cam 121 and the associated parts serve to actuate the carriage positively in a counterclockwise direction in Fig. 4, at the proper time, and to release the same for spring biased clockwise movement when the carriage has reached the proper level as determined by the stop means 98-99. Such counterclockwise movement of the carriage and the tone arm serves to disengage the roller 108 from the cam surface 109, and hence the throw-out lever 105 is permitted to resume its active relation wherein it will cooperate with the cam surface 106 to disengage the clutch 104 when the shaft 101 reaches its intermediate stop position in the next cycle of machine operation.

At appropriate points in the operating cycle, certain parts of the carriage 96, and the tone arm 95, are slightly lowered or slightly raised from the primary level determined by the stop mechanism 98-99, thereby to engage the needle carried by the tone arm with the sound track of the record in the initial portion of the cycle and disengage the needle from the sound track at substantially the end of the sound track. This is accomplished by means of a cam 125 and a medially pivoted lever 126 pivoted on the shaft 105', and a roller 126'' carried on one end of the lever 126. The forward end of the arm 126 has

an upwardly extending link 126B connected thereto, and the link 126B has an arcuate head 126C at its upper end which underlies the tone arm 95. Hence an upward movement of the link 126B is effective to raise the tone arm 95, while lowering movement of the link 126B serves to lower the tone arm 95 onto the record.

Thus the phonographic reproducing means 13 operates through a cycle of operation which is automatically terminated after a complete set of play directions has been reproduced.

The circuit connections for the present amusement apparatus are best shown in Fig. 8 of the drawings wherein it will be seen that two power lines 159 and 151 are led into the machine and connected to terminals 152 and 153. One side of the circuit to the motor 89 is provided from the terminal 153 by means of a wire 154 which is connected to one contact 111'' of the switch 111, the other contact 111' of the switch 111 being connected by the wires 155 and 156 to one side of the motor 89. The switch 111 is shown in detail in Fig. 5 of the drawings, and it will be recalled that this switch is opened at the end of a cycle of operation of the phonographic reproducing means 13 and must be again closed before another cycle of operation may be initiated. Such closure is effected under the control of the coin slot mechanism which, as will be hereinafter described, causes a solenoid 157 to be energized. Whenever the solenoid 157 is energized, an escapement device 158 mounted on the armature of the solenoid or relay 157 releases an escapement wheel 159 so that this wheel may rotate in a counterclockwise direction for one step under the biasing action of a spring 160. At this point a pin 161 on the escapement wheel 159 contacts the stop 162 so that further actuation of the relay 157 cannot cause further movement of the escapement wheel 159. The member 111'' of the switch 111 is biased by a spring 163 in such a manner as to urge the switch 111 to a closed relationship, and a hook-like device 164 carried on the switch element 111'' is engaged with the pin 161 so that when the pin is spaced from the stop 162, the switch member 111'' is held downwardly in a switch opening position. Therefore when the solenoid or relay 157 is energized to permit counterclockwise movement of the escapement wheel 159, the switch 111 is permitted to close. The switch 111 maintains this closed position until the arm 110 engages the switch arm 111', and at this time a pawl 165 carried by the switch arm 111' engages the escapement wheel 159 and returns the same one step in a clockwise position, in which position the escapement wheel is maintained by the escapement device 158. As soon as the cam arm 110 has passed the end of the switch arm 111', the arm 111' is withdrawn in an upward direction by the spring 163, thereby to open the switch 111.

The other side of the motor circuit is arranged to be controlled in part by the coin slot mechanism and in part by the manual starting button 25. To this end wires 170 and 171 in series are connected to one contact 172 of a switch 173 which is of the spring contact, normally closed type, and the other contact 174 of this switch is connected by means of a wire 175 to the other terminal 152. The switch 173 is closed at the time the phonographic reproducing means completes its operating cycle, and means is therefore provided for opening this switch as an incident to the vending of a playing card 17 and for closing this switch when the starting button 25 is actuated.

This means, of course, provides for a similar control to be effected by either one of the playing card vending devices, and but one of these circuit arrangements will be described. Thus an escapement wheel 180 is provided which is actuated in a clockwise direction against the action of a spring 180' when a relay device 182 is momentarily energized and which is released for movement in a counterclockwise direction when the relay device 181 is energized. This actuation is effected by the armature of the relay device 182 which acts as a pawl upon the ratchet wheel 180. The escapement wheel 180 carries a pin 183 so that when the escapement wheel 180 is in the position shown in Figs. 3 and 8, the pin 183 engages the switch contact 172 to open the switch 173. When the escapement wheel 180 is rotated one step in a clockwise direction due to momentary energization of the relay 182, the switch 173 is allowed to close and the other side of the motor circuit is closed.

One side of the coil of the relay 181 is connected to the terminal 153 by a wire 185 while the wire 186 extends to a terminal 187. From the terminal 187 the wire 188 extends through branch leads to one contact of each of the switches 59, the common contact of the switches 58 and 59 being connected by a wire 189 and a branch lead 189' to the other terminal 152. Thus when the switch 59 is closed momentarily by the passage of a coin through the coin mechanism, the solenoid 181 is energized.

The switch 59 also governs the solenoid or relay 157, a wire 190 connecting one side of the relay 157 to the terminal 153 and a wire 191 connecting the other terminal of the relay to the terminal 187.

When the escapement wheel 180 is released by the relay 181, the switch 173 is opened, and another switch 194 which is of the bridging type is closed as a part of an energizing circuit for the relay 182. Thus the switch 194 constitutes a conditioning switch which in response to the vending of a card 17, conditions the starting circuit which is ultimately governed by the push button switch 25. Thus the wire 175 from the terminal 152 is connected by a wire 195 to one terminal of the switch 194, and a wire 196 connects the other terminal of this switch to one terminal of the switch 25 and a wire 197 connects another terminal of the switch 25 to one side of the relay 182, while a wire 198 connects the other side of this relay to the wire 185, which it will be recalled, is connected to the terminal 153.

Thus when the cycle of operation of the amusement apparatus is terminated by the cam arm 110, thereby opening the switch 111 and breaking the motor circuit, the switch 173 in the other side of the motor circuit remains closed. When one of the card vending devices is operated, the coin closes the switches 58 and 59. This, of course, actuates the conditioning solenoid 46 of the card vending mechanism which is associated with the particular switch 58, and in addition it serves to energize the relays 157 and 181. The circuit from each switch 58 to its solenoid 46 is provided by a wire 46' from the outer contact of the switch 58 to one terminal of its solenoid 46, and by a wire 46'' from the other terminal of the solenoid to the terminal 153. Such energization of the relays 157 and 181 causes the switch 111 to be closed and the switch 173 to be opened. Hence the circuit to the motor 89 still remains open, but is adapted to be closed at any time under the will of the user, since the conditioning switch 194 has

been closed. Hence the user may, after he has obtained the desired number of playing cards 17, press the push button switch 25, thereby to energize the relay 182 and cause opening of the 5 conditioning switch 194 and closure of the switch 173 in the other side of the motor circuit. When the motor circuit is thus closed, the amplifier 16 is energized by virtue of a connection provided by wires 156' and 170' across the motor circuit. The phonographic reproducing means, therefore, 10 starts upon its operative cycle so as to give the playing directions required for playing of the game, and after a complete set of playing directions has been given, the operation or cycle of the 15 machine is terminated through the action of the cam arm 110.

From the foregoing it will be apparent that I have provided an amusement apparatus which enables a game such as the game of Bingo to be played by but a single player, and yet this amusement apparatus is such that the game may be played by a relatively large number of players. Through the use of the present amusement apparatus, the game may be played without the services of a play director, and hence the game may be played under many circumstances which heretofore would have prevented the playing of this or similar games.

Thus while I have illustrated and described a particular embodiment of my invention it is to be understood that this embodiment is capable of operation and modification and I therefore do not wish to be limited to the precise details set forth but desire to avail myself of such changes and alterations as fall within the purview of the following claims.

I claim:

1. In an amusement apparatus of the character described, a cabinet having an automatic phonographic reproducing means therein, said phonographic reproducing means including means for initiating a cycle of operation thereof and for automatically terminating said cycle, means for conditioning said initiating means for operation, manually operable starting means for operating said initiating means when said initiating means is conditioned by said conditioning means to thereby initiate a cycle of operation of said reproducing means, a phonograph record associated with said phonographic reproducing means and having directions recorded on the sound track thereof for the playing of a game, playing card vending mechanism adapted in each operation thereof to vend a card for playing said game, means operable as an incident to the operation of said playing card vending mechanism to operate said conditioning means and thereby condition such initiating means for operation by said manual starting means, and means operable as an incident to the operation of said manual starting means to return said conditioning means to an inactive relationship whereby said manual starting means is thereafter disabled until said playing card vending means is again operated.

2. An amusement apparatus of the character described comprising, a normally inoperative phonographic reproducing device including a record having a sound track bearing game-playing directions, and said device having electrically operated starting means and automatically operated stopping means for terminating a predetermined cycle of said phonographic reproducing device, an energizing circuit for said electrically energized starting means including a manually closable

normally open starting switch and a conditioning switch arranged to render said starting circuit ineffective, a playing card vending mechanism operable in each actuation thereof to vend a playing card, means associated with said playing card vending means operable to close said conditioning switch, and means operable as an incident to the starting of said phonographic reproducing means to cause opening of said conditioning circuit.

3. In a coin controlled amusement apparatus, a playing card vending mechanism, coin controlled mechanism governing the operation of said playing card vending mechanism, play-directing means for giving directions to the player or players, said play-directing means having a starting means including a starting circuit and having an automatic stopping means for terminating a cycle of operation of said play-directing means, said starting circuit including a conditioning switch governed by said playing card vending mechanism to condition said circuit for closure when said playing card vending mechanism is operated, and said starting circuit including a manually closable normally open starting switch adapted to be closed by a player after vending of one or more playing cards by said vending mechanism to thereby initiate a cycle of operation of said play-directing means, and means associated with said play-directing means and operable as an incident to the starting of said play-directing means to open said conditioning circuit.

4. In a coin controlled amusement apparatus of the character disclosed, a playing card vending mechanism, manual means governing the operation of said playing card vending mechanism, play-directing means for giving directions to the player or players, said play-directing means having a starting means, including a starting circuit, for initiating a predetermined cycle of operation of the play-directing means and having an automatic stopping means for terminating the cycle of operation of said play-directing means, said starting circuit including a conditioning switch governed by said playing card vending mechanism to condition said circuit for closure when said playing card vending mechanism is operated, and said starting circuit including a manually closable normally open starting switch adapted to be closed by a player after vending of one or more playing cards by said vending mechanism.

5. An amusement apparatus of the character described having a cabinet with an automatic phonographic reproducing means therein, said phonographic reproducing means including means for initiating a cycle of operation thereof and for automatically terminating said cycle, means for conditioning said initiating means for operation, manually operable means for operating said initiating means when said initiating means is conditioned by said conditioning means, said phonographic reproducing means having a plurality of phonograph records associated therewith, each having different playing directions recorded thereon for the playing of a game, and said phonographic reproducing means embodying means for rendering different ones of said records effective in at least certain of a series of cycles of operation of said reproducing means, playing card vending mechanism adapted in each operation thereof to vend a card for playing said game, means operable as an incident to the operation of said playing card vending mechanism to operate said conditioning means and thereby condition such initiating means for operation by said manual starting means, and means operable as an in-

cident to the operation of said manual starting means to return said conditioning means to an inactive relationship whereby said manual starting means is thereafter disabled until said playing card vending means is again operated.

6. In an amusement apparatus, an automatic phonographic reproducing means, said phonographic reproducing means including means for initiating a cycle of operation thereof and for automatically terminating said cycle, means for conditioning said initiating means for operation, manually operable means for operating said initiating means when said initiating means is conditioned by said conditioning means, phonographic record means associated with said phonographic reproducing means and providing sound track means embodying a plurality of different sets of playing directions recorded thereon for the playing of a game, said phonographic reproducing means including means for varying in predetermined series the set of playing directions to be reproduced in a cycle of operation of said reproducing means, playing card vending mechanism adapted in each operation thereof to vend a card for playing said game, means operable as an incident to the operation of said playing card vending mechanism to operate said conditioning means and thereby condition such initiating means for operation by said manual starting means, and means operable as an incident to the operation of said manual starting means to return said conditioning means to an inactive relationship whereby said manual starting means is thereafter disabled until said playing card vending means is again operated.

7. In an amusement apparatus of the character described a normally inoperative phonographic reproducing device including a record having playing instructions and directions recorded thereon under the direction of which one or more players may play the game to which said recorded directions relate, said phonographic device having starting means and stopping means automatically operated under control of a part of said reproducing device for terminating a predetermined cycle of operation of said phonographic reproducing device, control means for said starting means including a manually actuatable starting element and a conditioning element arranged to render said starting element ineffective, a playing card vending mechanism operable in each actuation thereof to vend at least one playing card pertaining to the game directions recorded on said record, and means associated with said playing card vending means operable upon said conditioning element to condition said starting element for operation, whereby a player may initiate operation of said phonographic reproducing means after one or more playing cards have been vended by said vending means.

8. In an amusement apparatus, play-directing means for giving play-directions to the player or players, said play-directing means having normally ineffective manually actuatable starting means and having an automatic stopping means for terminating operation of said play-directing means after a single cycle of operation thereof, said starting means including a conditioning element operable to an active relation to condition said starting means to be effective upon manual actuation thereof, playing card vending mechanism operable when actuated to vend a playing card and to operate said conditioning element to its active relation, and said starting means in-

cluding a manually actuatable element whereby a player may actuate said starting means when said conditioning element is in its active relation, thereby to initiate a cycle of operation of said play-directing means.

9. In an amusement apparatus of the character described, a card vending means having an operating means arranged for actuation as an incident to the vending of a card therefrom, automatic phonographic reproducing means operable in an operative cycle to give play directions relating to a predetermined game and having an energizing circuit for operating said phonographic reproducing means including two switches, means operable as an incident to the operation of said operating means of said card vending means for closing a first one of said switches, means operable by said phonographic means at the end of a cycle of operation thereof to open said first switch, manual means for initiating a cycle of operation of said phonographic reproducing means, means operable as an incident to the operation of said operating means of said card vending means for opening said second one of said switches, and means operable by said manual means for closing the second one of said switches.

10. In an amusement apparatus of the character described, a card vending means having an operating means arranged for actuation as an incident to the vending of a card therefrom, automatic phonographic reproducing means operable in an operative cycle to give play directions relating to a predetermined game and having an energizing circuit for operating said phonographic reproducing means including two switches, means operable as an incident to the operation of said card vending means for closing a first one of said switches, means operable by said phonographic means at the end of a cycle of operation thereof to open said first switch, means operable as an incident to the operation of said operating means of said card vending means to open the second one of said switches, and electrically operated

5 10 15 20 25 30 35 40 45

means for returning said second one of said switches to a closed position to start operation of said phonographic reproducing means.

11. In an amusement apparatus of the character described, a card vending means having an operating means arranged for actuation as an incident to the vending of a card therefrom, automatic phonographic reproducing means operable in an operative cycle to give play directions relating to a predetermined game and having an energizing circuit for operating said phonographic reproducing means including two switches, means operable as an incident to the operation of said card vending means for closing a first one of said switches, means operable by said phonographic means at the end of a cycle of operation thereof to open said first switch, means operable as an incident to the operation of said operating means of said card vending means to open the second one of said switches, electrically operated means for returning said second one of said switches to a closed position to start operation of said phonographic reproducing means, and a starting circuit for energizing said electrically operated means including a normally open manually operable switch and also including a second switch actuated to an open position as an incident to closure of said first-named second switch and actuated to a closed or conditioned position as an incident to opening of said first-named second switch.

NATHAN D. WYCKOFF.
